UNITED STATES PATENT OFFICE.

HENRY M. KEITH, OF ELDORADO, ILLINOIS.

CLOSET.

1,091,346.

Specification of Letters Patent. Patented Mar. 24, 1914.

Application filed March 15, 1913. Serial No. 754,406.

To all whom it may concern:

Be it known that I, HENRY M. KEITH, a citizen of the United States, residing at Eldorado, in the county of Saline and State 5 of Illinois, have invented new and useful Improvements in Closets, of which the following is a specification.

The invention relates to baths and closets and has for an object to provide a closet of 10 a simple and durable construction and which is normally in closed position and will be automatically opened when the seat ring is moved into operative position.

The invention embodies, among other features, a closet provided with water seals whereby, when the sealing lid is in closed position on the closet, the receptacle will be substantially air-tight.

The invention still further embodies 20 means whereby the water seals will be automatically kept filled with water and in which, when the seat ring is in inoperative position, the sealing lid will be in closed position, the said sealing lid being automatically movable into an open position 25 when the seat ring is swung into an operative position with respect to the receptacle.

In the further disclosure of the invention reference is to be had to the accompanying 30 drawings, constituting a part of this specification, in which similar characters of reference denote corresponding parts in all the views, and in which:

Figure 1 is a plan view of the closet 35 showing the same in closed position; Fig. 2 is a similar view showing the same in open position; Fig. 3 is a vertical sectional view taken on the line 3-3 in Fig. 2; Fig. 4 is a vertical sectional view taken on the line 40 4-4 in Fig. 1; Fig. 5 is a vertical sectional view of the supply tank showing the two-way valve connecting the main supply tank and the auxiliary tank forming a part thereof; and Fig. 6 is a similar view of the tank 45 showing the two-way valve in closed position with respect to the main supply.

Referring more particularly to the views, I disclose a closet 10 including a receptacle 11 having the upper end thereof terminating in an annular flange 12 cast or formed to provide an annular groove 13 adapted to be filled with water to provide a water seal 14. A top 15 is supported on the receptacle 11 by bolting or otherwise securing 50 the top thereto and the said top is provided with a central opening 16. The

edges of the top forming the opening constitute an annular flange 17 arranged to form a groove 18 adapted to be filled with water to constitute a water seal 19. A depending sealing flange 20 is formed on the under side of the top 15 and depends in the annular groove 13 to complete the water seal 14, as will be readily apparent, and it will be understood that the outer wall of 60 the groove 13 is higher than the inner wall thereof so that if the water in the groove should overflow the same will pass into the receptacle 11, this being also true of the outer wall of the groove 18 with respect to 65 the inner wall thereof and which is not quite as high as the outer wall so that an overflow of water in the groove 18 will result in the water overflowing and passing into the receptacle 11.

A sealing lid 21 is provided for the purpose of sealing the opening 16, the said sealing lid having a depending sealing flange 22 adapted to repose in the groove 18 and complete the water seal 19 in the same manner 70 that the sealing flange 20 depends in the groove 13. Secured to the sealing lid 21 is a bracket 23 including a slotted guide member 24 in which is received an arc shaped track 25 supported adjacent the receptacle 11 and in spaced relation thereto so that when the guide member 24 operates over the track in a horizontal plane the sealing lid 21 will be moved from closed position 75 into open position relatively to the opening 16 in the top 15 of the receptacle 11. The rear end of the bracket 23 is mounted to swing vertically on the front end of a pear shaped plate 26 and adapted to swing horizontally above the receptacle 11 and 80 having pivotal connection with the receptacle at its rear outer end, the said plate being provided with a vertical curved slot 27 commencing at the rear tapered end of the plate and extending inwardly and curved 85 and terminating at substantially the medial portion of the plate.

A seat ring 28 is carried on an actuating member 29 constituting a support for the seat ring and mounted to swing on the receptacle 11, with the said actuating member aligning with the entrance of the slot 27. Arranged to slide beneath the plate 26 is a lifting member 30 provided with an integral cam shaped head 31 adapted to engage the 95 bracket 23 and raise the sealing lid to move the sealing flange 22 out of the groove 18.

when a forward movement is imparted to the lifting member, the rear end of the said lifting member having a pin and slot connection with the actuating member 29, as shown, it being readily apparent that when the seat ring 28 is swung downwardly into operative position the lifting member will be advanced in front of the actuating member and, similarly, when the seat ring is swung upwardly into inoperative position, the lifting member will be retreated to normal and initial position owing to the rearward swing of the upper portion of the actuating member 29.

Now as shown in Fig. 1, when the sealing lid 21 is in closed and sealing position, as mentioned heretofore, and it is desired to open the receptacle and arrange the seat ring 28 in proper position on the receptacle, a downward forward pull is exerted on the seat ring which is normally in vertical position as shown in Fig. 3, and as the seat ring is swung forwardly and downwardly the actuating member 29, bearing against the lifting member 30, will advance the same beneath the plate 26 until the head 31 of the lifting member engages the bracket 23, thus raising the sealing lid 21 away from the receptacle sufficiently to remove the sealing flange 22 of the sealing lid from the groove 18. Now at the moment that the seat ring is swung forwardly and downwardly the actuating member 29 will enter the slot 27 and when it reaches the curved part of the slot, the plate 26 will be swung horizontally in view of the fact that the actuating member 29 has simply a vertical swinging movement and no lateral movement, whereas the plate is mounted to swing in a horizontal direction and perpendicularly to the swinging movement of the actuating member. Therefore, on the downward, forward, swinging movement of the seat ring the actuating member 29, operating in the slot 27 of the plate 26, will swing the plate horizontally, thus also swinging the sealing lid 21 horizontally to uncover the opening 16, the guide member 24 of the bracket 23 being adapted to operate over the track 25 described heretofore. Therefore, as the seat ring is swung downwardly the sealing lid will be moved into open position and the seat ring will take its place on the receptacle 11, thus covering the groove 18 as will be readily apparent by referring to the views. When it is desired to return the seat ring 28 to inoperative position the same is swung upwardly and rearwardly and in consequence thereof the actuating member 29 will be returned toward initial position and operate in the slot 27, thus returning the plate 26 to initial position and consequently returning the sealing lid 21 to closed position on the receptacle. A contractile spring 32 is preferably connected to the actuating

member 29 and the receptacle 11 for the purpose of facilitating the return movement of the actuating member.

Now in order to at all times provide perfect water seals 14 and 19 I provide a tank 33 including an auxiliary tank 34 having connection with the tank 33 by a suitable pipe 35. A pipe 36 is also provided and includes a branch pipe 37 terminating in the water seal 14, while the main portion of the pipe 36 terminates in the water seal 19, the upper end of the pipe 36 being arranged to terminate in a union 38 having connection with the pipe 35 connecting the tank 33 with the auxiliary tank 34, a two-way valve 39 being arranged to rotate in the union 38 and including an L-shaped passage 40 adapted to register with the portion of the pipe 35 carried by the auxiliary tank 34 and the portion of the pipe carried by the tank 33, when the valve is in one position, whereas when the valve is in another position the passage 40 will register with the pipe 35 connected to the auxiliary tank 34 and the pipe 36 for conveying water from the auxiliary tank to the water seals 14 and 19. The valve 39 carries an exterior lever 41 to which is pivotally connected one end of a rod 42 having the other end thereof pivotally connected to the actuating member 29. Now it will be apparent that when the seat ring is moved into operative position the forward swinging movement of the upper portion of the actuating member will exert a pull on the rod 42, thus actuating the valve 39 so that the passage 40 will form a connection between the tank 33 and auxiliary tank 34 and a portion of the water contained in the main tank 33 will therefore pass into and fill the auxiliary tank 34. Now when the seat ring is returned to an inoperative position a push will be exerted against the rod 42, thus actuating the valve to destroy the complete connection between the tank and auxiliary tank and establish a connection between the auxiliary tank and the pipe 36 so that the water contained in the auxiliary tank will flow through the pipe 36 and into the grooves 13 and 18 to fill the same and reopen the water seals 14 and 19, it being apparent that water will be admitted to the grooves of the water seals each time that the seat ring is moved into and out of operative position.

It will be understood that I do not limit myself to the particular kind of receptacle that is disclosed herein and that suitable traps of any ordinary and known construction may be used without departing from the spirit of the invention, it being further understood that the object of the invention is to provide a closet which will be in an air-tight condition when not in use and which must be unsealed before it can be used.

By providing a closet of this character

and as disclosed in the drawings, it will be apparent that the water seals are important adjuncts in retaining the closet in sealed position when it is not in use, the sealing lid being automatically movable into open position with respect to the receptacle, when the seat ring is swung downwardly into operative position while at the same time when the seat ring is swung into operative position and then returned to inoperative position water will be admitted to the grooves of the water seals to take the place of any water which may have evaporated or accidentally spilled therefrom.

Having thus described my invention, I claim:

1. In a closet, the combination with a receptacle provided with an opening, of a sealing lid for normally closing the opening, a plate mounted to swing horizontally on the receptacle and provided with a curved slot, an actuating member mounted to swing on the receptacle and extending through the curved slot of the plate to actuate the plate and move the sealing lid into and out of sealing position when the actuating member is operated, a seat ring carried by the actuating member and movable therewith, and means carried by the receptacle and movable by the actuating member to raise the sealing lid from closed position to permit the same to be swung horizontally into open position when the actuating member is operated.
2. In a closet, the combination with a receptacle provided with an opening, of a sealing lid normally closing the opening, a slotted plate carried by the receptacle and

movable horizontally, a pivotal connection between the sealing lid and the plate for moving the sealing lid horizontally when the plate is actuated, a bracket on the receptacle for guiding the sealing lid into or out of closing position, a spring-engaged actuating member mounted to swing on the receptacle and extending through the slot of the said plate for operating the plate when the said actuating member is operated, and a seat ring carried by the actuating member and movable therewith to occupy the place of the sealing lid when the sealing lid has been swung into open position by the operation of the said plate.

3. In a closet, the combination with a receptacle having a plurality of water seals, of a main supply tank, an auxiliary supply receptacle, a valve for controlling the supply tank, a pipe connecting the auxiliary supply tank with the said water seals, an actuating member mounted to swing on the receptacle, a valve for controlling the supply of fluid from the main supply tank to the auxiliary tank and from the auxiliary tank to the said water seals, and an actuating member mounted to swing on the receptacle and having connection with the valve for operating the same to fill the auxiliary tank with fluid and to permit the supply of fluid to flow from the auxiliary tank to the said water seals.

In testimony whereof I affix my signature in presence of two witnesses.

HENRY M. KEITH.
